GUIDE FOR ELECTRIC CLIPPERS

Joseph Guerra and Anthony Zemont, Crystal Lake, Ill.

Application April 22, 1958, Serial No. 730,169

3 Claims. (Cl. 30—201)

This invention relates to a guide for use with electric clippers.

The object of the invention is to provide a guide which can be readily attached to or detached from electric clippers whereby a person's hair can be accurately and readily cut to the desired length.

Another object of the invention is to provide a guide assembly for use with or attachment to a pair of electric clippers, and wherein the guide assembly will permit the hair of a person to be cut uniformly to any desired height, and wherein the guide assembly can be readily adjusted so that the hair can be cut to different lengths as desired.

A further object of the invention is to provide a guide assembly for clippers which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a perspective view illustrating the guide assembly of the present invention connected to the clippers.

Figure 2 is a top plan view of the guide assembly removed from the clippers.

Figure 3 is an end elevational view illustrating the guide assembly.

Figure 4 is a perspective view showing the parts disassembled.

Referring in detail to the drawings, the numeral 10 designates a set of conventional electric clippers which is provided with a slot 11, and the present invention is directed to a guide assembly for use with clippers such as the clippers 10 so that a person's hair can be cut uniformly or accurately. The guide assembly of the present invention is shown to comprise a base 12 which is adapted to be arranged below the clippers 10, and the base 12 includes a front curved or rounded portion 13. The upper portion of the base 12 is provided with a pair of spaced parallel channels or grooves 14, for a purpose to be later described. Each side of the base 12 is provided with a threaded aperture 15, Figure 4.

There is further provided a pair of spaced parallel similar plates which are each indicated by the numeral 16, and each plate 16 is provided with a plurality of spaced apart openings 17. An end of each plate 16 is rounded or curved as at 18. The numeral 19 indicates screw members or bolts which extend through the intermediate openings 17 and into threaded engagement with the apertures 15 in the sides of the base 12.

There is further provided a pair of similar spaced apart support members which are each indicated by the numeral 20, and each support member 20 includes a first portion 21 which is seated in a groove 14. Each support member 20 further includes second portions 22 which are arranged at right angles with respect to the

2

first portion 21, and the second portions 22 terminate in right angularly arranged third portions 23.

As shown in the drawings, there is further provided a pair of spaced parallel body members 24, and each body member 24 is provided with a pair of apertured ears 25 which are connected to the portions 23 of the support members 20.

Arranged adjacent one side of the base 12 is a bar 26 which is provided with slots or cutouts 27 that are adapted to register with adjacent portions of the support members 20, and one of the screw members 19 retains the bar 26 connected to a side of the base 12. Extending from the bar 26 and secured thereto or formed integral therewith is a tongue 28 which seats in the groove 11 or slot 11 of the clippers 10. The tongue 28 is provided with a recess or opening 29, Figure 4.

There is further provided a locking member or lever 30 which is pivotally connected to the base 12 by means of a pivot pin 31. The numeral 32 indicates a screw member which is arranged in engagement with an opening 33 in the rear of the base 12.

From the foregoing, it is apparent that there has been provided a guide for electric clippers wherein hair can be cut accurately and evenly and uniformly to different heights or lengths. The guide assembly of the present invention is adapted to be connected to a conventional set of clippers such as the clippers 10, and then the clippers 10 can be gripped in the hand in the usual manner and moved along a person's head so that the body member 24 will move along the head whereby the clippers will have their cutting members spaced a predetermined distance from the head so that the hair will be cut at the same length all over the head. This is especially suitable when hair is being cut in the so-called "crew cut" style.

The mounting of the guide is accomplished by inserting the tongue 28 in the usual slot 11 of the clippers 10 and the base 12 is arranged below the clippers 10 as shown in the drawings. The base 12 is provided with the spaced apart channels or grooves 14, and the pair of support members 20 have their portions 21 arranged in the grooves 14. The plates 16 are arranged alongside of the base 12 and are held in place by means of the screw members 19, and the body members 24 have their apertured ears 25 connected to the portions 23 of the support members 20, and then the outer ends of the portions 23 may be peened over so that accidental separation of the body members 24 from the portions 23 will be prevented. When it is desired to adjust the guide, the screw member 32 can be loosened so as to permit shifting movement of the support member 20 in the rearmost groove 14 whereby the body members 24 can be moved to different positions with respect to the base 12, and then the screw member 32 can be tightened so as to retain the parts immobile in their adjusted positions.

The front portion of the base 12 is rounded as at 13, and the front ends of the body members 24 are also rounded, and the front ends of the plates 16 are also rounded or curved so as to insure that these parts will glide smoothly over the hair or head.

The parts can be made of any suitable material and in different shapes or sizes. The opening 29 in the tongue 28 provides sufficient clearance for the usual nylon cam on the clippers.

The guide assembly is adapted to be snapped on or attached to various conventional makes of electric clippers and can be used by professional barbers as well as by persons cutting hair in the home or the like. The guide insures that there will be an accurate and straight crew cut and the guide can be adjusted for any height of hair depending upon the desires of the customer or other person. The guide will eliminate the necessity of free hand

cutting and the members 24 will slide on the head without pressure from the operator so that the hair can be cut more readily and in less time.

In use, the friction type lever 30 is opened or moved to the position shown in Figure 1 and then the clippers 10 are placed on the base 12 and the tongue 28 is inserted into the slot 11 in the clipper from the left side of the clipper and the tongue 28 rests with spring pressure on the bottom of the cutter only and will not touch the top of the movable cutter mechanism. Then, the lever 30 is moved to closed position, as for example as shown in Figures 2 and 3 so as to lock the tongue 28 in place, and then the adjustable runners or members 24 are adjusted for height desired. The tongue 28 and bar 26 can be changed or replaced so that the guide assembly will fit different makes or types of conventional clippers, and when the lever or locking member 30 is to be rotated or moved, the screw member 31 can be loosened, and after the lever 30 has been moved to the desired position, the screw member 31 can be tightened.

Minor changes in shape, size and rearrangement of details coming within the field of invention claimed may be resorted to in actual practice, if desired.

We claim:

1. A guide for electric clippers having a slot therein, said guide comprising a base positioned below the clippers, said base including a front curved portion and flat side faces, there being a pair of spaced parallel grooves in the upper portion of said base, there being threaded apertures in each side of the base, a plate arranged contiguous to each side of the base, the front end of each plate being shaped arcuately, there being a plurality of spaced apart openings in each plate, a screw member extending through one of the openings and into threaded engagement with a threaded aperture, a pair of spaced apart support members each having a first portion extending through certain of the openings in said plates and seated in said grooves, each support member further including second portions arranged at right angles to said first portion, said second portions terminating in third portions, a pair of spaced parallel body members each provided with apertured ears connected to the third portions of said support members, a bar arranged contiguous to one side of the base, and said bar being provided with cutouts therein for registering

with the adjacent portions of the support members, a tongue extending from said bar and seated in the slot in the clippers, and a lever pivotally connected to the base, and said lever being mounted for movement into and out of locking engagement with respect to said tongue.

2. A hair cutting guide assembly comprising a base, including a front curved portion and flat side faces, there being a pair of spaced parallel grooves in the upper portion of said base, there being a threaded aperture in each 10 side of the base, a plate arranged contiguous to each side of the base, the front end of each plate being shaped arcuately, there being a plurality of spaced apart openings in each plate, a screw member extending through one of the openings in a plate and into threaded engagement 15 with a threaded aperture, a pair of spaced apart support members each having a first portion extending through certain of the openings in said plates and seated in said grooves, each support member further including second portions arranged at right angles to said first portions, 20 said second portions terminating in third portions, a pair of spaced parallel body members each provided with apertured ears connected to the third portions of said support members, a bar arranged contiguous to one side of the base, and said bar being provided with cutouts therein for registering with the adjacent portions of the support members, a tongue extending from said bar, and a lever pivotally connected to the base and mounted for movement into and out of locking relationship with respect to said tongue.

3. A guide for electric clippers having a slot therein, said guide comprising a base positioned below the clippers, a plate arranged contiguous to each side of the base, a pair of spaced apart support members, a pair of spaced parallel body members connected to said support members, a bar arranged contiguous to one side of the base, a tongue extending from said bar and seated in the slot in the clippers, and a lever pivotally connected to the base, and said lever being mounted for movement into and out of locking engagement with respect to said tongue.
